UNITED STATES PATENT OFFICE.

LOUIS H. BROWN, OF NEW YORK, N. Y.

CAN AND STOPPER THEREFOR.

1,124,999.

Specification of Letters Patent. Patented Jan. 12, 1915.

Application filed May 26, 1914. Serial No. 841,149.

To all whom it may concern:

Be it known that I, LOUIS H. BROWN, a citizen of the United States, and a resident of the city of New York, borough of Manhattan, in the county and State of New York, have invented a new and Improved Can and Stopper Therefor, of which the following is a full, clear, and exact description.

10 Among the principal objects which the present invention has in view are: to provide a device of the character mentioned to form a closure joint both interiorly and exteriorly; to provide a tight-fitting stopper 15 and means inherent therein for facilitating the removal thereof; to provide a stopper of the character named, having a relatively inexpensive construction; and to provide a can and stopper to prevent the accumulation 20 of the material with which the can is charged at the pouring edge thereof.

Drawings.—Figure 1 is a vertical section of a can and stopper therefor constructed and arranged in accordance with the present invention: Fig. 2 is a side view showing the under face of the stopper; Fig. 3 is a view similar to Fig. 1, the parts thereof being shown in separated relation; Fig. 4 is a vertical section of a can and stopper therefor, the stopper being constructed in accordance with the modified form of the invention; Fig. 5 is a side view, showing the under face of the stopper shown in Fig. 4; Fig. 6 is a side view of a can and a vertical section of a stopper therefor, said can and stopper being shown in separated relation and as constructed in accordance with the modified form of the invention.

Description.—As seen in the drawings the can 11 is preferably provided with a clear passage and a standing terminal flange 14, the outer edge whereof remains preferably raw or reduced to a cutting edge. At the base of the flange 14, the metal forming the can 11 is laterally expanded and longitudinally contracted to form an annular flange shoulder 15. The stopper to fit the can above described is constructed of any yielding and slightly resilient material. As shown in the drawings, the stopper 16 is constructed of wood of a substantially soft and pithy character. The body of the stopper 16 is shaped to form a central boss or filler 17. The boss or filler 17 is extended 55 beyond the body of the stopper to form a guide member therefor to aid in inserting

the stopper within the can 11. Flush with the sides of the boss 17, the body of the stopper has formed therein a cut or scarf 18, usually produced by the insertion of a 60 knife blade or edge. It is preferred that no material shall be removed from the scarf 18 so that the pressure of the sides thereof on the adjacent sides of the flange 14, when forced therein, will operate to clean said 65 flange and to remove any adhering portions of the material with which the can 11 is charged. To protect the stopper 16, and to reinforce the same, a metal cap 19 is provided. The cap 19 is furnished with an annular flange 20, which infolds and is pressed upon the side edge of the stopper 16. To hold the stopper 16 within the cap 19, the annular flange 20 is curled over the projecting side of the stopper 16 to form a facing 70 21 for the under side of the stopper, and also an edge to force the side of the flange 14, slightly inward. In service, the facing 21 receives the pressure of any tool which is employed for prying the stopper from the 75 can, to open the same.

It will be noted that the facing 21 in the preferred form, and the extended flange 22 in the modified form of the invention are both, when in service, disposed in line with, 80 and separated from the flange shoulder 15. This construction in both forms provides a rest for a tool inserted below the overhang of the stopper to lift the same from the 85 can 11.

Claims:

1. In combination, a can having a straight flange pouring opening; a stopper for said can having a tube formed in correspondence with said flange and opening, adapted to receive said flange and to press upon the exterior and interior surfaces thereof; a metal cover for said stopper, said covering being shaped to form an exposed inturned flange; and an annular extended flange formed on 95 said can adjacent said inturned flange and separated therefrom when in service position.

2. A can, comprising a standing thin-edged flange, forming the opening thereof; an annular flange shoulder formed integral with said can and extended laterally therefrom adjacent the edge of said upstanding flange; a stopper for said can having an annular groove for receiving the thin edge 105 of said upstanding flange; a metal cap covering said stopper, said cap having an 110

nular flange covering the edge of said stopper; and a facing flange inturned below said stopper, said facing flange being juxtaposed to said shoulder on said can when in service 5 relation.

3. A can, comprising a standing thin-edged flange, forming the opening thereof; an annular flange shoulder formed integral with said can and extended laterally therefrom adjacent the edge of said upstanding flange; a stopper for said can having an annular groove for receiving the thin edge of said upstanding flange; a metal cap cover-

ing said stopper, said cap having an annular flange covering the edge of said stopper; and a facing flange, said facing flange being juxtaposed to said shoulder on said can when in service relation. 15

In testimony whereof I have signed my name to this specification in the presence of 20 two subscribing witnesses.

LOUIS H. BROWN.
